TYPOGRAPHICAL COMPOSING MECHANISM

Louis Rossetto, Flushing, N. Y., assignor to Mergenthaler Linotype Company, a corporation of New York

Application June 5, 1951, Serial No. 230,046

3 Claims. (Cl. 199—27)

This invention relates to typographical composing machines such as Linotype machines, wherein matrices, when released from a magazine by the manipulation of a keyboard, pass downwardly or through a vertical channeled raceway or front plate and onto the upper stretch of an inclined endless conveyor belt from which they pass through a guide throat or chute to an assembler, wherein they are composed in line under the influence of a constantly rotating star wheel.

As ordinarily constructed, the assembler throat, at its lower side, is constituted by a pair of curved guide rails partially enclosing the star wheel and whereon the matrices are discharged by the conveyor belt; and, at its upper side, the throat is constituted by a so-called "chute spring" which is arranged to engage the side faces of the matrices and confine them to their proper path of travel just before they enter the assembler. Although the matrices, passing under the control of the chute spring, are caused to follow the curvature of the rails until they engage the star wheel, it is also important that they be further guided and restrained against deflection upwardly by the star wheel as they pass from under said spring. For this reason, the chute spring usually is formed at its lower end with a pair of horizontally disposed prongs which are intended to hold the matrices down as they are about to enter the assembler. In practice, however, it has been found that the aforesaid chute spring is incapable of handling matrices above a certain thickness because the extent of its displacement by extremely thick or head-letter matrices is so great that the horizontally disposed prongs either fail to function at all, or snap down upon the upper ends of the matrices as they clear the spring and thus interfere with rather than assist in their assemblage. As a result, the matrices frequently clog or pile up in the chute or throat and must be removed by hand, slowing up the work of composition.

The present invention aims to overcome the above and other objections, first, by dispensing with the star wheel entirely and substituting therefor oscillatory means operative to push the matrices directly into the assembler as they leave the throat and, second, by replacing the chute spring with a pair of fixed rails disposed directly over those on the lower side of the throat and adapted to guide the descending matrices only by their projecting ears as they pass therethrough.

In the accompanying drawings, the invention has been shown merely in preferred form, by way of example, and therefore is not limited to any specific form or embodiment except insofar as such limitations are specified in the appended claims.

Referring to the drawings:

Fig. 1 is a front elevation of the assembling devices immediately concerned with the present improvements and showing the oscillating pusher device in its retracted position;

Fig. 2 is an elevation similar to Fig. 1, but on a larger scale, showing the oscillating pusher device in its active position;

Fig. 3 is a vertical section taken on the line 3—3 of Fig. 2;

Fig. 4 is a detail perspective view of the pusher element and its supporting arm; and indicating, in broken lines, the housing bracket for the arm actuating spring; and

Fig. 5 is a horizontal section taken on the line 5—5 of Fig. 2.

As previously stated, after the matrices X are released from their storage magazine (not shown), they pass

2

downwardly through a channeled raceway or front plate A onto a constantly driven inclined conveyor belt B which discharges them one after another, in the order of their release, into a throat C leading to the assembler elevator D. Here, they are composed in line with spacers Y and the line thereafter delivered to the casting mechanism, all as is well understood in the art.

The matrices X are formed as usual with upper and lower projecting ears x which generally are located at one side of the individual matrices, that side being the rear or following one. When, therefore, the matrices are delivered to the conveyor belt B, they will lie upon their rear sides and their projecting ears (which in themselves vary but slightly in thickness) will pursue substantially the same path to the assembler elevator without regard to the body thickness of the matrices.

According to the present invention, and as best shown in Figs. 1 and 3, the upper side of the assembler throat C comprises a pair of curved guide rails C¹ and the lower side of said throat a pair of curved guide rails C², the rails C¹ being secured by clamping screws c to the rear wall of the channeled raceway A, and the rails C² also being secured to said wall by screws and dowel pins c¹. The upper guide rails C¹ (Fig. 2) are held properly spaced apart by sleeves c² mounted on the shank portions of the screws c, while the lower guide rails C², for the same reason, are connected in the usual way to the front and rear sides of a spacing block c³. If it should be desired to handle matrix fonts wherein certain of the thicker matrices are "back milled" or, in other words, have their projecting ears offset from their rear side faces, the upper guide rails C¹ of the throat, by removing the screws c, could readily be interchanged with another pair having a different curvature and spaced a slightly greater distance from the lower rails C². Or, instead of removing the upper guide rails C¹ completely for replacement in such instances, they could easily be made adjustable toward and from the lower rails C² by forming them with short slots instead of drilled apertures to accommodate the screws c. As in all commercial Linotype machines, the assembler throat C and certain parts immediately adjacent thereto are normally concealed by a cover plate C³ (indicated by the broken lines in Fig. 1) which serves primarily as the front side wall of the throat and is hingedly mounted at its lower left hand corner so that it may be swung downwardly out of the way, when access to the throat and the receiving end of the assembler D is desired.

In carrying out the present invention, oscillatory means are employed for pushing the matrices, one after another as they leave the throat C, directly into the assembler elevator D and at the same time stack them in line against the upstanding finger E¹ of the well known assembler slide E. Such means, as best shown in Figs. 2, 3 and 4, include a vertically disposed bell crank lever F mounted on a pivot screw f and actuated by a compression spring F¹ under the control of an edge cam G, the latter being constantly rotated by a chain and sprocket drive J in a 1 to 1 ratio from the shaft B¹ of the belt driving pulley B², and arranged to engage an antifriction roller f¹ attached to one arm F² of the bell crank lever. The other arm F³ of the lever F (Fig. 2) rises vertically from the pivot screw f alongside the entrance to the assembler elevator D, and the actuating spring F¹ for said lever directly engages the arm F³. As shown best in Figs. 1 and 2, the spring F¹ is mounted in a horizontally disposed housing bracket H located immediately below the spacing block c³ for the lower guide rails C² and also fastened to the rear side wall of the channeled raceway A. At one end, the bracket H (Figs. 2 and 5) is bifurcated to accommodate the adjacent edge of the vertical arm F³ of the lever F, and at its opposite end it is provided with a sustaining screw H¹ for the compression spring F¹, said screw being capable of an adjustment, when desired, to regulate the potential energy of said spring and in any case to tension it sufficiently to overcome the resistance presented by the assembler slide E through its upstanding finger E¹. A lock nut h, mounted on the screw H¹ and seated against the bracket H, holds the screw in its adjusted position.

The vertical arm F³ of the lever F (Figs. 2, 4 and 5)

is equipped with a pusher element F^4 pivotally connected thereto by a screw stud f^2 and provided with a light pull spring F^5 for holding it yieldingly in its active position (Figs. 1 and 2) against a stop pin f^3 projecting forwardly from the front face of said arm. The pusher element F^4 is formed with a rounded nose portion f^4 arranged to engage the rear side faces of the matrices as they leave the throat C on their way to the assembler D , and the cam G is formed with high and low portions g^1 and g^2 , respectively. Consequently, whenever a matrix in the course of its descent strikes the nose portion f^4 of the pusher element, the latter will yield momentarily (see the dotted line showing in Fig. 2) to permit the passage of the matrix and then be allowed to snap back to its normal or active position as the vertical arm F^3 of the bell crank lever F is swung clockwise by rotation of the cam G , against the tension of the compression spring F^1 to its inactive position shown in Fig. 1. In order that the pusher element F^4 may more readily be displaced or rocked out of the way by the descending matrices regardless of their thickness, the pull spring F^5 is located immediately below and just off dead center with the pivotal axis of said element, when the latter occupies its normal position against the stop pin f^3 (Fig. 2). In other words, the arrangement is such that the nose portion f^4 of the pusher element will not interfere or appreciably retard the descent of the thinner and lighter matrices as they are composed in line.

It should now be clear that matrices X passing through the throat or chute C and entering the assembler elevator D will be stacked one after another in line against the upstanding finger E^1 of the assembler slide E as the pusher element F^4 is continuously oscillated by the bell crank lever F .

What is claimed is:

1. Typographical composing mechanism including, in combination, an assembler wherein the matrices are composed in line, a conveyor belt for delivering the matrices to the assembler, a guide throat or chute leading from the discharge end of the belt to the entrance of the assembler, an oscillatory pusher element arranged to engage the matrices one by one as they leave the throat during the composition of the line and advance them directly into the assembler, a pivoted bell crank lever capable of being rocked through a limited number of degrees in opposite directions to effect the oscillations of the pusher element at the proper rate, said lever having one arm extending upwardly adjacent the entrance to the assembler and carrying at its free end the pusher element which is pivotally mounted thereon for a rocking movement in a downward direction from its operative position thereon so as to be capable of being rocked out of the way by

the descending matrices, and said lever having its other arm extending away from the assembler entrance and carrying at its free end a roller, a spring acting upon the upwardly extending arm of the bell crank lever for effecting the matrix advancing stroke of the pusher element, a rotary cam arranged in engagement with the roller on the other arm of the bell crank lever for controlling the action of the spring and for effecting the return stroke of the pusher element against the tension of the spring, and driving means for rotating the cam continuously and thus oscillating the pusher element continuously.

5 2. A combination according to claim 1, including a stop pin for locating the pusher element in its upper operative position on the bell crank lever, and a light pull spring for holding said element yieldingly against the stop pin.

10 3. Typographical composing mechanism including, in combination, an assembler wherein the matrices are composed in line, a conveyor belt for delivering the matrices to the assembler, a guide throat or chute leading from the discharge end of the belt to the entrance of the assembler, an oscillatory pusher element arranged to engage the matrices one by one as they leave the throat during the composition of the line and advance them directly into the assembler, a pivoted bell crank lever capable of being rocked through a limited number of degrees in opposite directions to effect the oscillations of the pusher element at the proper rate, said lever having one arm extending upwardly adjacent the entrance to the assembler and carrying at its free end the pusher element, and said lever having its other arm extending away from the assembler entrance and carrying at its free end a roller, a spring acting upon the upwardly extending arm of the bell crank lever for effecting the matrix advancing stroke of the pusher element, a rotary cam arranged in engagement with the roller on the other arm of the bell crank lever for controlling the action of the spring and for effecting the return stroke of the pusher element against the tension of the spring, driving means for rotating the cam continuously and thus oscillating the pusher element continuously, and means for regulating the tension of the spring which actuates the bell crank lever.
